GRINDING MACHINE

Francis A. Jimerson, Athens, Pa., assignor to
Ingersoll-Rand Company, Jersey City, N. J., a
corporation of New Jersey

Application October 22, 1938, Serial No. 236,518

5 Claims. (Cl. 51—95)

This invention relates to grinding machines, and more particularly to a grinding machine for sharpening and gauging drill bits of the detachable type.

One object of the invention is to facilitate the operations of placing the drill bit on the grinding machine and removing it therefrom.

Another object is to enable the grinding machine to be readily adjusted to accommodate drill bits of different sizes.

Still another object is to effect the automatic removal of the drill bit from contact with the grinding wheel upon completion of the grinding operation.

Other objects will be in part obvious and in part pointed out hereinafter.

In the drawings accompanying this specification and in which similar reference numerals refer to similar parts,

Figure 1 is a front elevation, partly broken away, of a grinding machine constructed in accordance with the practice of the invention.

Figure 2 is an end elevation, partly broken away, of the form grinding wheel and its work holder.

Figure 3 is an elevation, partly broken away, showing a front view of the profile or form grinding wheel and its work holder.

Figure 4 is a plan view of the gauge grinding end of the machine.

Figure 5 is an end elevation of the gauge grinding portion of the machine.

Figure 6 is an enlarged longitudinal view, in elevation and partly broken away, of the gauge grinding portion of the machine.

Figure 7 is a transverse view taken through the work gripping element on the line 7—7 in Figure 6.

Figure 8 is an elevation, partly in section, taken through Figure 1 on the line 8—8 and showing a driving connection.

Figure 9 is a transverse view taken through Figure 8 on the line 9—9.

Figure 10 is a transverse view taken through Figure 5 on the line 10—10, and

Figure 11 is an elevation, partly in section, of a detail.

Referring more particularly to the drawings, 20 denotes the grinding machine in its entirety and 21 the work piece shown as being in the form of a detachable drill bit of the cruciform type and having the usual gauge surfaces 22 and cutting edges 23 on its wings which the grinding machine is intended to redress.

In the form of the invention shown, the grind-

ing machine 20 comprises a frame 24 upon which is mounted, among other elements, a motor 25 that drives the grinding machine. On the top of the frame 24 is a tray 26 and a mounting 27 for the grinding and feeding elements of the machine.

The mounting 27 comprises a casing 28 having end walls 29 and 30 in which are apertures 31 and 32, respectively, to accommodate a shaft 33. The ends of the shaft extend exteriorly of the casing 28 and carry grinding wheels 34 and 35. On the portion of the shaft 33 lying between the walls 29 and 30 is a sheave 36 which is aligned with a sheave 37, on the motor shaft 38, and a pair of belts 39 are trained over the sheaves 36 and 37 to transmit movement from the motor to the shaft 33.

Preferably the apertures 31 and 32 are of considerably larger diameter than the shaft to accommodate housings 40 and 41, respectively, for bearings 42 of the anti-friction type which are held against shoulders 43 on the shaft by nuts 44 threadedly engaging the shaft 33. The housings 40 and 41 are connected to the casing 28 by bolts 45.

One of the openings in the casing 28 through which the shaft extends, in this instance the opening 32, is of ample diameter so that whenever a belt requires attention it may be moved or inserted through the opening 32.

In a more specific sense the grinding wheels 34 and 35 are, respectively, profiling or forming and gauge grinding wheels. The wheel 34 has a substantially V-shaped periphery that corresponds to the notches or spaces between the cutting wings of the drill bit. More specifically, the periphery of the wheel 34 has two inclined surfaces 46 that converge in the middle of the wheel and the inclination of these surfaces conform with that of the sides of the cutting wings. The degree of inclination of the surfaces 46 depends, of course, upon the type of bit for which the wheel 34 is intended and may be varied by suitable dressing apparatus in a manner well understood.

The grinding wheel 34 is secured to and held in concentric relationship with the shaft 33 by the usual cheek plates 47, and a spacer 48 acting against the outermost cheek plate 47 serves as 50 a seat for a nut 49 threaded on the end of the shaft 33 to clamp the wheel 34 securely between the cheek plates 47.

The grinding wheel 34 is enclosed by a guard 55 mounted on the outer side of the wall 29 of the casing 28 and having an aperture 51 through

which the shaft 33 extends. In the opposite end of the guard 50 is an opening 52 to permit of access to the grinding wheel and said opening is normally closed by a cover plate 53. In the front or working side of the guard is an opening 54 through which the work piece, such as the drill bit 21, may pass to contact with the grinding wheel 34.

The work holder supporting the drill bit 21 and which is denoted in its entirety by 55, is also mounted upon the guard 50. It is arranged between a pair of lugs 56 on the guard and attached pivotally thereto by a bolt or rod 57 extending through one lug 56 and the holder 55 and threaded or otherwise affixed to the other lug 56. The bolt 57 is longer than the combined width of the elements through which it extends and on the projecting portion of the bolt is a coil spring 58 which tends to balance the weight of the work holder 55 in order to prevent a too free pivotal movement of the work holder about the bolt 57.

One end of the spring 58 is anchored to the work holder and the other end of the spring to a washer 59 that seats against the head 60 of the bolt 57 and held against rotary movement with respect to the bolt in any well known manner.

The portion of the work holder 55 engaging the bolt 57 constitutes a rocker 61 and has a pair of wings 62 which lie on opposite sides of a bearing block 63 carrying a handle 64 for rocking the work holder about the bolt 57. The block 63 is bored to receive an arbor 65 of which an end 66 extends into the drill bit 21 to support it for grinding. The arbor 65 may be freely rotatable in the bearing block 63. It has a collar 67 that seats against one end and a knurled knob 68 abuts the other end of the bearing block to prevent endwise movement of the arbor with respect to the bearing block. The knob 68, moreover, serves as a convenient grip member for rotating the arbor.

To the end that the bearing block may be angularly adjusted with respect to the rocker 61 it is secured pivotally to the wings 62 by a bolt 69 extending through the wings 62 and through the lower portion of the bearing block. In the upper portion of the bearing block is a second bolt 70 which extends through arcuate slots 71 in the wings 62 and has a nut 72 threaded thereon for clamping the wings 62 securely to the sides of the bearing block. The foregoing arrangement makes possible a quick adjustment of the bearing block in instances where the profile of a working bit requires a certain angular position of the arbor 65 with respect to the working face of the grinding wheel 34 in order to avoid the formation of high or low centers on the drill bit.

Although the work holder 55 may be oscillated about the pivot bolt 57 by means of the handle 64 it has been found advantageous to provide means whereby the work may be performed in part by pressure of the operator's foot. To this end the rocker 61 is provided with a lug 73 having a depression 74 to receive the end of a rod 75 of which the opposite end rests upon a treadle 76 mounted upon a bar 77 on the frame 24.

The handle 64 and the treadle 76 afford a choice of means for applying force to the work holder to move it toward the grinding wheel or, as has been found to be a preferred mode of operation, the treadle may serve to move the drill bit toward the grinding wheel and the handle 64 to retract the drill bit. This division of labor is

desirable since it is inadvisable to permit of extended period of contact between the work and the wheel because of danger of burning the work or glazing the grinding surfaces. The drill bit is, in consequence, thrust against the grinding wheel for only a brief period and then quickly withdrawn. As will be readily appreciated, this requires a succession of oscillations of the work holder at close intervals and may be accomplished with less fatigue to the operator if both the hand and foot are used to actuate the work holder.

Inasmuch as the work holder 55 is mounted upon the guard 50 it is essential that these elements be shiftable relatively to the grinding wheel 34 to make possible the correct position of the work holder with respect to the grinding face, otherwise the angular relationship of the arbor 65 to the grinding surface of the wheel would change accordingly as the diameter of the grinding wheel diminishes through wear or with different lengths of work pieces. In furtherance of this end, means are provided to enable the guard to be moved laterally of the grinding wheel and comprise a slide 78, of dovetail shape, which may be an integral portion of the guard 50 or formed as a separate member and suitably attached to the guard. The slide 78 is arranged in a guideway 79 in the side of the casing 28 and the guideway thus forms the sole support for the guard. A screw 80 in threaded engagement with a lug 81 on the slide 78 serves to move the slide 78 longitudinally of the guideway 79.

The screw 80 is provided with a handle 82 located conveniently near the operator's position for rotating the screw, and a pair of collars 83 attached to the rearmost end of the screw 80 and lying on opposite sides of a rib 84 on the adjacent portion of the casing 28 serve to hold the screw 80 against endwise movement.

Sufficient clearance exists between the collars 83 and the rib 84 to enable the screw 80 to be rotated freely. Thus, whenever it becomes necessary to move the guard and the work holder 55 to a new position, as for a redressing of the grinding wheel 34 or the replacement of the grinding wheel with one of larger diameter, the screw 80 is rotated in the required direction to move the guard toward or away from the grinding wheel.

The wheel 35 differs from the wheel 34 principally in that it has a substantially true cylindrical grinding surface. It is supported and held in concentric relationship with the shaft 33 by plates 85 of which the innermost one seats against a spacer 86 abutting the nut 44, and a nut 87 threaded on the end of the shaft 33 and seating against the outermost plate 85 clamps the wheel 35 securely between the plates 85. The wheel 35 is, moreover, covered by a guard 88 which is secured to the casing 28 by the bolts 45 securing the bearing housing 41 in position, and in the opposite end of the guard 88 is an opening 89 that is normally closed by a cover plate 90.

The guard 88 also preferably serves as a mounting for the devices which support the drill bit during the grinding thereof and effect feeding movement of the drill bit with respect to the grinding wheel. The guard 88 accordingly has an integral sleeve 91 which extends longitudinally of the machine, at a lower elevation than the shaft 33, and in the sleeve 91 are a pair of bushings 92 which serve as renewable bearing surfaces for a reciprocating rod 93.

The rod may be freely rotatable in the bushings 92 and supports a work holder denoted in its entirety by 94. The work holder is mounted on a bracket 95 attached to the rod 93 and comprises, as casing parts, a head 96 and a cap 97 seated on the end of the head 96. On the opposite end of the head 96 is a reduced extension 98 of which the periphery serves as a bearing surface for a collar 99 forming an integral portion of a bracket 100 positioned in front of the grinding wheel 35 and above the sleeve 91. The collar 99 is split and is clamped fixedly to the extension 98 by a pinch bolt 101.

In its assembled position the bracket 100 lies directly beneath the drill bit 21 so that when the drill bit is released from the work holder it may drop upon the bracket 100 and thence roll over the upper surface 102 of the bracket which is inclined toward the tray 26.

The bracket 100 is of approximately C-shape and an arm 103 thereof lies between the transverse planes of the grinding wheel and the bearing housing 41. In the side of the arm 103 confronting the drill bit 21 is a bearing 104 of the anti-friction type in which is inserted a cup 105 having a flange 106 seating against the inner surface of the arm to exclude abrasive matter from the bearing 104. A packing member 107 between the flange 106 and the bearing 104 serves as a further protection for the bearing 104.

In the periphery of the cup, near its innermost end, is a spring ring 108 which seats against the inner race of the bearing 104 to lock the bearing to the cup and thereby make it possible to remove both from the arm as a unit.

The inner race of the bearing 104 may, moreover, be fitted snugly on the cup 105 and the interior 109 of the cup serves as a receptacle for the stem 110 of a center 111 having grooves 112 in its end surface to accommodate the cutting edges 23 of the drill bit. A spring ring 113 engaging the stem 110 and the wall of the bore 109 holds the center 111 against endwise movement with respect to the cup 105.

The center 111 is freely rotatable with the drill bit 21 which is supported in grinding position by a chuck 114 threaded into the end of a hollow spindle 115 extending longitudinally of the head 96 and into the cap 97. The gripping element of the chuck 114 comprises, for example, a stem 116 which extends into the socket 117 of the drill bit 21 and has a series of radial slots 118 to accommodate keys 119 which are collectively encircled by a garter spring 120 tending to move the keys 119 toward the axis of the chuck. The inner surfaces 121 of the keys 119 seat upon the coniform surface of an expander 122 in the chuck 114 for pressing the keys 119 into gripping engagement with the drill bit.

The expander is in the form of a rod and has a head 123, at its innermost end, slidable in an enlarged portion 124 of the bore 125 in the spindle 115. A spring 126 encircling the expander acts against the head 123 with one end and with its other end against the chuck 114 to move the

and has arranged thereon a pair of anti-friction bearings 131 that are held on the stem 130 by a washer 132 held in position by a screw 133 threaded into the end of the stem 130.

5 The outer races of the bearings 131 are disposed slidably in the open end of a cup 134, slidable in the cap 97, and containing a spring 135 that seats against the outer race of the innermost bearing 131 and acts, in the relaxed position of the gripping elements, to maintain the outer race of the outermost bearing 131 in abutment with a spring ring 136 arranged in the mouth of the cup 134 to retain the bearings 131 in the cup.

The spring 135, in effect, is a resilient transmission member and serves the function of transmitting force to the expander for driving the keys 119 against the drill bit and such force is applied to the spring 135 and the train of elements leading to the keys 119 by a toggle 137 attached to the cup 134.

15 In order to control the tension of the spring 135 the cup 134 is adjustable relatively to the toggle. A preferred mode of accomplishing this is to thread the cup upon a bolt 138 the head of 20 which is pivotally connected to a pin 139 seated in a pair of wings 140 on the toggle 137. A nut 141 on the bolt 138 seats against the end of the cup 134 and locks the bolt to the cup.

The portions of the wings 140 through which 25 the pin 139 extends constitute one end of the toggle 137. On the other end of the toggle and lying in parallelism with the pin 139 are trunnions 142 that extend pivotally through ends of straps 143 arranged above and below the toggle 30 and having their other ends pivotally connected to pins 144 in the upper and lower surfaces of the cap 97. The straps 143 may be held on the trunnions 142 and the pins 144 in any suitable manner, as by cotter pins 145 placed in the ends 35 of the trunnions and the pins. A grip member 40 146 on the toggle 137 provides a convenient lever for rocking the toggle about the trunnions 142.

The straps 143 are of suitable length to avoid sharp side thrust of the cup 134 against the 45 wall of the cap 97 and, therefore, excessive wear upon the cooperative surfaces of these elements as a result of the repeated movement of the cup in the cap 97 incident to the operation of the toggle.

50 The work holder 94 is pivotally mounted upon the bracket 95 so that it may be angularly adjusted with respect to the grinding surface of the wheel 35 in accordance with the angle of the gauge surfaces 22. In the arrangement shown 55 the outer race of an anti-friction bearing 147 seated in a lower wall 148 of the head 96 and extending part way into a bore 149 in the bracket 95 serves to centralize the head 96 with the bracket. On the portion of the head 96 adjacent 60 the bracket 95 are flanges 150 which seat upon flanges 151 on the bracket 95 and have arcuate slots 152 to receive clamp bolts 153 threaded into the flanges 151. The slots 152 are of ample length so that the work holder 94 may be rocked to the positions of angular adjustment necessitated by different angles of gauge surfaces 22.

The operation of adjusting the work holder to the correct angular position with respect to the grinding surface of the wheel 35 may be quickly accomplished by partly unthreading the screws 153 and rotating the work holder about its axis until the gauge surface of the drill bit lies flush against the grinding surface of the wheel 35. After the work holder has been thus positioned the flanges 150 and 151 are again clamped

together for holding the work holder immovable with respect to the bracket 95.

The bearing 147 serves its usual function as a bearing for a shaft 154 extending through the bore 149 and having a pinion 155 at its upper end. The pinion 155 meshes with a gear 156 keyed to a sleeve 157 encircling the hollow spindle 115 which is slidable in the sleeve 157. On the periphery of the spindle 115 are splines 158 that interlockingly engage splines 159 in the sleeve 157 to prevent relative rotary movement between the two, and the sleeve 157 is supported by anti-friction bearings 160 and 161 in the cap 97 and the head 96, respectively.

Suitable packing members 162 and 163 are placed in the extension 98 to encircle the spindle 115 and the sleeve 157, respectively, for preventing the passage of abrasive matter into the head 98.

The lower end of the shaft 154 extends into a bore 164 in the rod 93 and has a reduced extension 165 carrying a pinion 166 which abuts an anti-friction bearing 167 in the adjacent portion of the bracket 95. A spacer 168 encircling the shaft 154 abuts the bearings 167 and 147 to prevent endwise movement thereof with respect to the shaft 154.

The shaft 154 and associated gearing constitute parts of a train of driving elements for effecting constant rotary movement of the chuck 114 during the grinding of a drill bit. The power employed for this purpose is also provided by the motor 25 and is transmitted from the shaft 33 by a belt 169 and sheaves 170 and 171 secured, respectively, to the shaft 33 and a counter-shaft 172 arranged in a gear casing 173 mounted on the frame 24. The shaft 172 is supported by anti-friction bearings 174 and 175 in the gear casing 173 and carries a clutch disc 176. A complementary disc 177 faced with friction material 178 is mounted upon a longitudinally shiftable shaft 179 disposed slidably in a sleeve 180 supported by a bearing 181 on the frame 24.

The shaft 179 is moved, for separating the clutch discs, by force applied to a treadle 182 mounted upon the lower portion of the frame 24. A link 183 connects the treadle to an arm 184 of a bell crank 185, and the bell crank rocks upon a pivot 186 on the frame 24 and has an arm 187 to engage a collar 188 on the shaft 179 for moving the clutch disc 177 out of contact with the clutch disc 176. A spring 189 interposed between the collar 188 and the end of the sleeve 180 acts to move the shaft 179 toward the shaft 172, and a spring 190 secured to the frame 24 and to the treadle 182 normally maintains the treadle in position in which the arm 187 will be out of engagement with the collar 188.

An end of the shaft 179 projects outwardly beyond the bearing 181 and is slidably interlocked with a sheave 191 so that either may move freely with respect to the other. Owing to this arrangement the sheave may at all times remain in alignment with a sheave 192 on a shaft 193 extending longitudinally of the bore 164 in the rod 93. A belt 194 trained over the sheaves 191 and 192 transmits motion from the shaft 179 to the shaft 193, and a pinion 195 on the innermost end of the shaft 193 meshes with the pinion 166 for delivering power to the shaft 154 and thus to the work holder. Preferably, the shaft 193 is provided with anti-friction bearings 196 which are seated in a sleeve 197 threaded into the end of the rod 93.

An additional service of the shaft 172 is that

of transmitting the power required for reciprocating the rod 93 and to drive a pump 198 which supplies cooling liquid to the grinding wheels 34 and 35. The driving connections to both are located in the gear casing 173 and that acting to drive the rod 93 comprises a worm 199, on the shaft 172, meshing with a worm gear 200 attached to a shaft 201. The shaft 201 is supported by anti-friction bearings 202 in the gear casing 173 and projects exteriorly of the gear casing into a crank 203 to which it is locked by a set screw 204.

In the outer surface of the crank 203 and extending longitudinally thereof is a T-slot 205 for the accommodation of a T-bolt 206 serving the function of a crank pin. The bolt 206 is readily adjustable in the slot 205 and is clamped fixedly to the crank 203 by a nut 207 threaded on the bolt. The bolt 206 is provided with a bushing 208 lying in the end of a connecting rod 209 of which the opposite end is connected to a rocker arm 210 extending upwardly through the frame 24 and terminating in the longitudinal plane of the rod 93. A pivot 211 supported by the frame 24 extends through an intermediate portion of the rocker arm, and in the upper end of the rocker arm is a pivot 212 to which is connected an end of a link 213 having its other end connected to the rod 93.

The link 213 is adjustable and comprises a yoke 214 which is attached to the pivot 212 and threadedly connected to a screw 215 having a ball head 216 which lies in a partly cylindrical socket 217 in the rod 93 and is held in the socket by a bushing 218 threaded into the rod. The screw 215 carries a knurled flange 219 to enable the screw to be conveniently rotated with respect to the yoke 214, and a lock nut 220 on the screw and seating against the end of the yoke 214 locks the screw 215 against unauthorized rotation with respect to the yoke 214.

The link 213 provides a convenient means for adjusting the range of movement of the drill bit with respect to the grinding surface of the wheel 35. As will be appreciated, it would be undesirable to reciprocate the gauge surfaces of the drill bit to move into and out of the plane of the grinding surface of the wheel. In practice, therefore, the link 213 is so adjusted that the gauge surfaces never move entirely out of the plane of the grinding surface and this may be conveniently accomplished by shortening or lengthening the link.

The pump 198 which, as previously stated is also driven from the shaft 172, is of the submersible type. It extends into a tank 221 forming a reservoir for cooling liquid and has a discharge pipe 222 which may lead to the grinding wheels 34 and 35 to deliver liquid to the grinding surfaces. In the arrangement shown the pump is supported by the gear casing 173 and connected thereto by a distance piece 223 which houses a pump shaft 224 carrying a pinion 225 that meshes with a pinion 226 on the shaft 172.

Unlike the work holder 55, which is actuated by manual pressure, the work holder 94 is actuated mechanically for feeding the work toward the wheel 35. Such movement is effected in step-by-step fashion by means including a ratchet wheel 227 integral with or suitably attached to a cam 228. The ratchet wheel and the cam are mounted rotatively on a shaft 229 and the ratchet wheel carries a hand-wheel 230 for rotating the ratchet wheel and the cam 228 manually on the shaft 229. The shaft 229 extends into and is affixed, as by means of a set screw 231, to an arm

232 having a bearing portion 233 which encircles the free end of the rod 93 and is held thereon by a shoulder 234 on the sleeve 197.

The arm 232 extends along the side of the grinding machine and carries, at its rearmost end, a pair of rollers 235 which embrace a rod 236 supported by the mounting for holding the arm 232 against rotative movement with respect to the rod 93. The arrangement is such that during the reciprocatory movement of the rod 93 the rollers 235 will roll along the rod 236.

The cam surface 237 of the cam is in the form of an involute and moves or rotates under a cam follower 238 carried by a bell crank 239 attached to the arm 232 by a pivot 240 extending through the angle of the bell crank 239. The high and low points of the cam surface 237 lie directly on opposite sides of a notch 241 which accommodates the cam follower 238 in the non-feeding position of the work holder, and in the periphery of the ratchet wheel 227 and in the same radial plane as the notch 241 is a blank surface 242 which forms a rest for a pawl 243 adapted to engage the teeth 244 of the ratchet wheel.

The pawl 243 lies in a substantially horizontal plane above the ratchet wheel 227 so that it may drop into engagement with the teeth 244 by gravity and is pivotally connected to an end of a rocker arm 245. The rocker arm is of V-shape and is secured pivotally to the bearing portion of the bracket 95 by a pin 246. On the intermediate portion of the arm 245 is a button 247 engaging the end of a spring 248 of which the other end is connected, in the present instance, to a pin 249 on the tray 26. Thus, as the rod 93 moves to and fro the rocker arm 245 will be caused to tilt and in that way shift the pawl 243 to new positions on the ratchet wheel.

The arm 245 is rocked about the pivot 246 by a buffer 250 lying in the path of the elbow 251 of the rocker arm. The buffer is slidably adjustable in a bore 252 in a casing part of a machine, as for example the sleeve 91, and is locked in the different positions to which it may be adjusted by a set-screw 255 threaded into the sleeve 91.

The cam follower 238 is held, with a required degree of firmness, against the cam 228 by a spring 257 attached to a lug 258 on the bearing portion of the arm 232, said lug being one of a pair that serve as guides for the end of the bell crank 239 carrying the cam follower 238. The other end of the spring 257 is connected to a clip 259 secured to the free end of the other arm 260 of the bell crank.

To the end that the work holder may be readily adjusted with respect to the grinding wheel 35 for placing it in approximately the correct grinding position for a drill bit of a given diameter the bracket 95 is connected to the arm 260 of the bell crank 239 by an adjusting screw 261. The screw 261 carries a hand-wheel 262 for rotating it and is journaled in a bearing 263 having a trunnion 264 rotatable in the bracket 95. The threaded portion of the screw engages a nut 265 arranged in a slot 266 in the bell crank and having trunnions 267 extending rotatably into the arm 260.

In the operation of the device, a drill bit 21 is placed on the arbor 66 and the work holder 55 is then oscillated about the pivot 57 to place the cutting teeth of the bit into contact with the grinding surface of the wheel 34. After the contiguous sides of a pair of cutting wings have been ground the arbor 66 is rotated to a new posi-

tion to bring other surfaces of the cutting teeth into position for grinding.

This operation may be repeated until all the sides of the cutting wings have been ground. The 5 drill bit 21 is next placed on the chuck 114 and the toggle 137 is then rocked about the trunnions 142 to move the chuck 114 toward the center 111. This movement of the toggle imparts pressure through the spring 135 to the rod 127 which will 10 act against the expander 122 and cause the keys 119 to be pressed outwardly against the skirt of the drill bit for securing the bit to the chuck 114. The force imparted by the toggle for actuating the chuck mechanism will also cause the 15 wings of the drill bit to be pressed firmly into the grooves 112 of the center 111.

During the placing of the drill bit on the chuck 114 the treadle 182 is depressed to break contact between the clutch discs 176 and 177 so that the 20 chuck 114 will remain stationary. After the drill bit has been secured to the chuck the treadle 182 is released and the spring 189 will then shift the shaft 179 to reestablish frictional contact between the clutch discs and movement will be 25 transmitted from the shaft 172, through the connecting train of elements, to the chuck 114 for rotating it.

In the event that the spacing of the work 30 holder 84 with respect to the grinding surface of the wheel 35 is unsuited for a drill bit of a given diameter the screw 261 may be rotated to tilt the work holder the distance required to bring the gauge surfaces 22 of the drill bit into contact with the wheel. The ratchet wheel 227 35 may then be given a partial turn to move the blank surface 242 from beneath the pawl 243 and to bring a ratchet tooth into position for engagement with the pawl. This movement of the ratchet wheel will also move the low point of the 40 cam surface 237 beneath the follower 238.

During the ensuing operation of the machine the chuck will be constantly rotated and will reciprocate relatively to the grinding wheel to distribute wear over the entire grinding surface of the wheel. On each inward stroke of the rod 93 the rocker arm 245 abuts the buffer 250 and will be rocked about the pivot 246 and cause the pawl 243 to rotate the ratchet wheel and the cam. Upon each thrust of the pawl 243 the follower 238 is raised slightly by the cam and the work holder is thereby moved toward the grinding wheel 35 in step-by-step fashion.

This operation will continue until the ratchet wheel has been rotated to a position in which the blank surface 242 again lies beneath the pawl. The notch 241 will then also reach a position beneath the cam follower 238 which will drop into the notch 241, thus permitting the spring 257, by its force exerted on the bell crank 239, to tilt the work holder away from the grinding wheel.

The devices effecting the different movements described herein operate in such manner that the gauge surfaces 22 will be nicely reconditioned 65 during the time required by the ratchet wheel to make a complete revolution, and when the drill bit is completely ground pressure is again applied to the treadle 182 to disconnect the shaft 179 from the shaft 172. The drill bit may then be removed and another placed on the chuck 114 preparatory to a new grinding operation.

In the event that the grinding wheel 35 be replaced with one of greater or less width the stroke of the rod 93 may be changed by moving the crank pin 206 to a different position in the 70 75

slot 285. This may be quickly and conveniently done by unthreading the nut 287 and moving the crank pin toward or away from the shaft 281 and again clamping the crank pin to the crank 283 by means of the nut 287. In this way the stroke of the work may be nicely adjusted to assure utilization of the entire grinding surface of the wheel and to prevent uneven wearing thereof.

I claim:

1. In a grinding machine, a mounting, a grinding wheel supported by the mounting, a work holder adjustable angularly with respect to the grinding wheel to change the axis of the work holder to an inclined position with respect to the axis of the grinding wheel, a horizontal pivot for the work holder, a feeding device for effecting feeding movement of the work holder, means for moving the work holder with respect to the grinding wheel, means for actuating the feeding device in response to movement of the first said means, and means controlled by the feeding device for tilting the work holder from the grinding wheel upon completion of a grinding operation.

2. In a grinding machine, a mounting, a grinding wheel supported by the mounting, a work holder adjustable angularly with respect to the grinding wheel to change the axis of the work holder to an inclined position with respect to the axis of the grinding wheel, a reciprocatory member serving both as a support and a pivot for the work holder, a feeding device to rotate the reciprocatory member during alternate strokes of the reciprocatory member for effecting a step-by-step feeding movement of the work holder, and means for automatically causing actuation of the feeding device during a stroke of the reciprocatory member.

3. In a grinding machine, a mounting, a grinding wheel supported by the mounting, a work holder, a reciprocatory support for the work holder, a rotary cam for tilting the work holder toward the grinding wheel, a ratchet wheel for the cam, a pawl on the reciprocatory support to engage the teeth of the ratchet wheel, and an

abutment on the mounting to engage the pawl during a stroke of the reciprocatory support and thereby cause the pawl to rotate the ratchet wheel and the cam in step-by-step fashion.

4. In a grinding machine, a mounting, a grinding wheel supported by the mounting, a casing, a support for the casing, means for effecting reciprocatory movement of the support during the grinding of a work piece, means for rotating the support about its axis to actuate the work holder toward the grinding wheel, a work holder in the casing, a work-centering member in axial alignment with the work holder, a bracket affixed to the casing to support the work-centering member, a toggle to force the work holder into engagement with a work piece and to press such work piece against the work-centering member, a spring for transmitting force from the toggle to the work holder, and an adjusting device for controlling the tension of the spring to vary the distance between the work holder and the work-centering member.

5. In a grinding machine, a mounting, a grinding wheel supported by the mounting, a casing, a support for the casing, means for effecting reciprocatory movement of the support during the grinding of a work piece, means for rotating the support about its axis to actuate the work holder toward the grinding wheel, a rotary work holder in the casing having a work-gripping element, a bracket on the casing, a center in the bracket in axial alignment with the work-gripping element, a toggle for forcing the work-gripping element into engagement with a work piece and to force such work piece into engagement with the center, cushioning means for transmitting force from the toggle to the work-gripping element, an adjusting device for the cushioning means to vary the distance between the work holder and the center, a feeding device for effecting feeding movement of the work holder, and a driving connection in the reciprocatory support and the casing for rotating the work holder.

FRANCIS A. JIMERSON.
